BLANKING AND FORMING PRESS

James H. Kindelberger, Inglewood, Calif., assignor to North American Aviation Corporation, Inglewood, Calif., a corporation of Delaware

Application August 7, 1936, Serial No. 94,790

2 Claims. (Cl. 164—28)

This invention relates to a blanking and forming press especially adapted to the blanking and/or the forming of irregular shapes made from sheet metal.

It is one of the principal objects of this invention to devise a blanking and a forming press of relatively simple and rugged construction which will operate rapidly and easily to blank out and/or form irregular shapes from sheet aluminum, alloys thereof, or other materials, and in which the male portion of the blanking and/or forming die is opposed by a resilient member preferably of rubber.

A further object is to arrange the machine so that the blanking and/or forming operation will be progressively performed.

Other objects and advantages of the invention will become apparent as the nature of the same is more fully understood from the following description and accompanying drawings wherein is set forth what is now considered to be a preferred embodiment. It should be understood, however, that this particular embodiment of the invention is chosen principally for the purpose of exemplification and that variations therefrom in details of construction or arrangement of parts may accordingly be effected and yet remain within the spirit and scope of the invention as the same is set forth in the appended claims.

In the drawings:

Figure 1 illustrates a side elevational view partially in section to more clearly show some of the operating details of the machine.

Figure 2 illustrates a plan view of a typical blanking die.

Figure 3 illustrates a sectional view taken substantially in the plane of line 3—3 of Fig. 1.

Figure 4 illustrates a fragmental sectional view taken substantially in the plane of line 4—4 of Fig. 1.

Figure 5 illustrates a fragmental view partially in section of the resilient member as it would appear during a blanking operation.

Figure 6 illustrates a modified form of the resilient member.

Figure 7 illustrates one specific type of forming die.

Fig. 8 illustrates a section taken substantially in the plane VIII—VIII of Fig. 7.

In its preferred form, the invention illustrated in Figures 1 to 5, inclusive, may include a frame 10 of appropriate form to support the several elements of the machine. As may be observed in Figures 1, 3 and 4 the frame may be provided with a pair of spaced ways 11 and 12, preferably

grooved to accommodate the antifriction rollers 13. A table 14 is provided with grooved ways 15 and 16 for engaging rollers 13 and thereby providing an antifriction reciprocatory mounting for the table. A power cylinder 17 is provided for driving the table back and forth. The cylinder at one end may be directly bolted to the frame while at its opposite end may be provided with a head 18 having a common form of stuffing box 19 through which the piston rod 20 operates.

It will be understood that the piston rod carries upon its inner end a piston forming a fluid seal with the cylinder bore in the usual manner. The outer end of piston rod 20 is connected to the table as by means of a wristpin 21 which extends through the enlarged end of the rod and the bifurcated bracket 22 preferably formed integral with the table.

The table is reciprocated by the cylinder by supplying thereto hydraulic pressure through one or the other of pipes 23 and 24. The valve mechanism for controlling the supply of pressure fluid to one or the other of said pipes while opening the opposite pipe to atmospheric pressure has not been shown as there are a great many control valves on the market suitable for this purpose.

The top surface of table 14 comprises a working surface, that is a surface to which any one or more of a number of blanking dies 25 may be securely mounted as by means of cap screws 26. A plan view of one blanking die is shown in Figure 2, wherein the contour of the die is clearly shown. It will be understood that dies of other contours may be readily substituted for the particular die shown.

Opposed to the table is a pressure roller 27 carrying a resilient member 28. The resilient member may be mounted upon the roller in the manner of a tire, as shown in Figure 6, or belted therearound, as shown in Figures 1, 3 and 5. In these last figures the resilient member is in the form of an endless belt plying between the roller and an adjustable idler pulley 29. The roller is journaled to the free end of a cradle 30 (Figures 1 and 3) as by means of shaft 31. The cradle is pivotally mounted upon the machine frame by means of pivot shaft 32. That portion of the cradle which supports the pressure roller is preferably bifurcated to provide supporting bearings 33 upon opposite ends of the pressure roller shaft 31. The idler roller 29 is adjustably mounted in the cradle, as is clearly shown in Figures 1 and 3 wherein the opposite sides of the bifurcated portion of the cradle are slotted as at 34 to receive

the square bearing blocks 35 and adjusting screws 38 screw-threaded through lugs 37, acting to properly position the idler pulley with relation to the pressure roller whereby the resilient member 5 28 may be tensioned to a desired degree. This feature also provides sufficient slack in the resilient member to facilitate mounting of the roller, pulley and resilient member in the cradle. It is preferable to provide at least the pressure roller 10 with side flanges 38 to limit the deflection of the resilient member during the blanking operation.

Means are provided for controlling the position of the cradle and thereby the position of the resilient member with relation to the top surface 15 of the blanking die to thereby control the shearing action of the resilient member against the cutting edges of the die. This means is preferably in the form of a hydraulic cylinder 40 which at its upper end is pivotally connected to the upper end of the frame as by means of pivot shaft 41. The frame at this point is bifurcated to provide a bearing at each side of the cylinder. A cylinder head 42, having the usual stuffing box 43, is bolted to the lower end of the cylinder and a piston rod 44 carrying a piston within the cylinder, not shown, extends through the stuffing box and at its lower end is pivotally connected to the free end of the cradle by the pivot pin 45. Pressure lines 46 and 47 connect the opposite 20 ends of the cylinder to a hydraulic control valve, not shown, whereby the position of the cradle 25 may be elevated or lowered to suit the desired operating condition.

In some cases it may be desirable to mechanically drive the pressure roller during the blanking operation. This feature may or may 30 not be made use of and in some instances it may be entirely eliminated. The means for driving the pressure roller herein shown includes providing table 14 with a rack 46 and from this element driving the roller through a train of gears. The gear train may include a driving gear 47 journaled upon the cradle pivot shaft 32 which not only meshes with the rack but also with an 35 idler gear 48 journaled upon the cradle by means of shaft 49. The idler gear in turn meshes with a driven gear 50 fixedly mounted upon the pressure roller shaft 31. As the pressure roller is fixedly mounted upon this same shaft the rotation of the gears will cause a rotation of the roller. It should be noted that the gearing is so arranged 40 and proportioned as to cause the roller and thereby the resilient member to rotate in the same direction and at substantially the same surface speed as the surface of the die to which it is opposed during the movement of the die. As 45 the pressure roller is driven directly from the table, it follows that movement of the table in either direction will cause a corresponding rotation of the resilient member carried by the roller and that the surface speed of the resilient member will always correspond to the speed of the table.

The machine may be operated in the following 50 manner: With the table retracted as shown in Figure 1, and a blanking die mounted thereon, a sheet of aluminum or other material may be placed upon the die. Next, by means of cylinder 40, the resilient member may be raised above the material and then the table advanced by means of cylinder 47 until the forward edge of the die lies substantially under the pressure roller whereupon the cradle can be forced downwardly by means of cylinder 40 until the resilient member 55 assumes a position similar to that of Figure 5.

In this figure it will be noted that the forward end of the material has been sheared down over the die. The table need not be stopped while bringing the resilient member into shearing relation with the die and as a result the die and surface of the resilient member will roll in pressure contact, whereby the shearing action will progressively travel from one end of the die to the other. Upon completion of the blanking operation the blanked piece of metal, together with 10 the portion trimmed therefrom, may be removed from the die and another piece of material placed upon the die and during the return stroke of the table the blanking operation repeated.

By providing rollers 51 adjacent each side of 15 the pressure roller for holding the material upon the die during the initial engagement of the resilient member therewith, the cradle may be maintained in adjusted position and the table reciprocated back and forth completing a blanking 20 operation for each stroke thereof.

From the above description, it will be appreciated that the machine operates easily and quickly to perform the blanking operation.

The progressive blanking action is one of the 25 important features of the invention as it greatly reduces the pressure or thrust necessary to complete a blanking operation. Heretofore it has been the practice to use a relatively large powerful, and as a result, slow-acting hydraulic press 30 for this purpose. When using the usual hydraulic press a die is placed upon the press anvil, material to be blanked placed upon the die, a block of rubber placed upon the material, whereupon the rubber block is forced down upon the material by the ram of the press until sufficient pressure has been exerted upon the rubber block to suddenly bring about the complete shearing 35 of the surplus material around the die. By this method the material around the entire contour 40 of the die is severed at the same instant, thus requiring great pressure and as the material gives way more or less suddenly, causing the press to jump in a more or less destructive manner.

Contrasting the hydraulic press method with 45 that of this invention, it is found that a relatively small amount of pressure is necessary to cause the material to shear at one point or location of the die, and thereafter even less pressure is needed to carry on the shearing operation as it 50 progresses from one end of the die to the other. There is no destructive jarring of the machine, and a very much smaller and less heavily built machine, operating much more rapidly, will perform the blanking operation.

The rollers 51 may be mounted upon the cradle in the manner shown in Figure 1. These rollers may or may not be used, this depending upon the type of work and manner of operating the machine.

The machine of this invention may be used as a forming press, that is, instead of shearing the surplus material from the blank around the die, the die 60, (Figs. 7 and 8) may be of the forming 65 type, that is, the die may have depressions 61 or other configurations into which the material under treatment will be forced by the pressure roller as the die with its material is moved thereunder. The machine is capable of many other uses as 70 will be appreciated by those skilled in this art.

Having fully described the invention, it is to be understood that it is not limited to the details herein set forth, but the invention is of the full scope of the appended claims.

I claim:

1. In a progressive pressing device, a frame, a die supporting table reciprocally mounted upon said frame, means for reciprocating the table, a cradle pivotally mounted at one end to said frame, a pressure roller journaled in said cradle in spaced relation to the cradle pivot, an idler roller journaled in the cradle, a resilient pressing member belted around the pressure and idler rollers, a driving rack carried by the table, gear means journaled upon the pivotal center of said cradle mounting and engaging said rack, driving means between said gear and pressure roller, and means for controlling the movement of the free end of the cradle toward or from the table.

15

2. In a progressive pressing device, a frame, a die supporting table reciprocally mounted upon said frame, means for reciprocating the table, a cradle pivotally mounted at one end to said frame, a pressure roller having a resilient tread journaled in said cradle in spaced relation to the cradle pivot, a driving rack carried by the table, gear means journaled upon the pivotal center of said cradle mounting and meshing with the rack, driving means between said gear and pressure roller, and means for controlling the movement of the free end of the cradle toward or from the table.

JAMES H. KINDELBERGER. 15
